UNITED STATES PATENT OFFICE.

JOHN E. L. HARbold, OF WORTHINGTON, KENTUCKY.

CAR-COUPING.

SPECIFICATION forming part of Letters Patent No. 286,198, dated October 9, 1883.

Application filed April 18, 1883. (No model.)

To all whom it may concern:

Be it known that I, JOHN E. L. HARbold, of Worthington, in the county of Jefferson and State of Kentucky, have invented certain new and useful Improvements in Car-Coupling Apparatus, of which the following is a specification.

The object and result of my improvement is to furnish a simple, economical, and efficient 10 appliance by which railroad-cars of varying heights may be surely and safely coupled without the necessity of the brakeman getting in between the cars for the purpose of guiding the link into its proper place. The results are 15 obtained by the mechanism illustrated in the annexed drawings, making part hereof, and in which the same letters refer to the same parts in the different views.

Figure 1 is a perspective view, showing my 20 improved apparatus as moved into position for guiding the link into the socket of the draw-head for the purpose of coupling the cars. Fig. 2 is a perspective view of my improvement as it hangs in its position when the cars 25 are in motion and it is not being used for the purpose of coupling. Fig. 3 is a top view, showing my improved apparatus detached from the car. Fig. 4 is a side elevation of my 30 improved apparatus, showing the journal-shaft cut near the sliding link guide and frame, for the purpose of giving an unobstructed view of the same.

The letter M refers to the draw-head approaching the draw-head of the car that is to 35 be connected, and the letter L refers to the link attached to the approaching car. The link L is brought in proper line with the socket of the draw-head of the opposite car by raising or lowering the flanged head (lettered

C) of the sliding link-guide formed by the fixed 40 bars, (lettered F and E,) and connecting with the journal-shaft, (marked G,) which hangs below the draw-head on hangers, (marked K.) The flanged head of the link-guide C, attached to the sliding bar, (lettered D), moves in and out 45 of the recess between the fixed bars E and F, attached to journal-shaft, (marked G.) The letters J and I refer to straps attached to fixed bars E and F, and passing outside of the sliding bar D, for the purpose of making a sure 50 guide for its inward and outward motion. The link-guide (formed and referred to by the letters C and D) moves out when not in use, and when raised into position by the operator handling the levers (marked H) on either side 55 of the car the link is brought into proper position, and the link-guide moves back with the force of the car's motion, and thus maintains the proper position of the link until the connection is complete by the pin (referred to by the 60 letter O) dropping through the link and into its socket.

Having thus fully described and explained the construction and operation of my improvement, what I claim as new, and desire to secure 65 by Letters Patent, is as follows:

The movable link-guide sliding in and out between fixed bars, connecting with movable shaft suspended from the car, substantially as shown, for the purpose set forth. 70

In testimony that I claim the foregoing I have hereunto affixed my hand this 14th day April, 1883.

JOHN E. L. HARbold.
